UNITED STATES PATENT OFFICE.

WILLIAM FRANK ZIMMERMANN, OF WAVERLY, NEW YORK, ASSIGNOR TO INGERSOLL-RAND COMPANY, OF JERSEY CITY, NEW JERSEY, A CORPORATION OF NEW JERSEY.

TIE-TAMPER PISTON.

Application filed August 6, 1926. Serial No. 127,617.

This invention relates to pneumatic percussive tools and more particularly to the type in which there is provided a reciprocating piston adapted to strike against the 5 shank of the tool.

In tools of this type when the piston becomes worn leakage sometimes prevents the hammer from starting to reciprocate. It is an object of this invention to prevent the 10 hammer piston from becoming air bound and to make the hammer quick to respond under all conditions.

The invention will be more clearly understood by reference to the following description and the drawings in which,

Figure 1 is a longitudinal section of a hammer tool constructed in accordance with the practice of the invention,

Figure 2 is a longitudinal section through 20 the piston of the hammer tool, and

Figure 3 is a cross section through the piston, taken along the line 3—3.

Referring to the drawing, the invention is shown as applied to a pneumatic tie 25 tamper substantially as shown in U. S. Patent No. 1,470,622, granted to Francis A. Jimerson October 16, 1923, comprising a cylinder A within which a hammer piston B is adapted to reciprocate striking against 30 a tamper bar suitably supported within a front head D. The tie tamper is guided by a handle E having a pair of grips F and G. The handle E is preferably provided with a flange H which is attached to a cylinder flange J by means of suitable bolts K.

The cylinder A is provided with two bores of different diameter, the larger bore L being at the rear end of the cylinder and the smaller bore O being forward. A port 40 P is arranged to communicate with both bores L and O to conduct live motive fluid and exhaust to and from the rear bore L. To this end the larger bore L is provided with two annular grooves Q and R and the smaller bore O is provided with an annular groove S. An exhaust port T is provided in an enlarged chamber U forward of the bore O.

The hammer piston B is of the differential type in which one area is constantly exposed to line pressure of the motive fluid. Accordingly, the piston B is provided with 50 a head V of substantially the diameter of the cylinder bore L and a tail portion W slidably fitting the smaller cylinder bore O.

The face of the piston head V adjacent the tail portion W is constantly exposed to live pressure of motive fluid entering the cylinder from an inlet port X in the large bore L.

Motive fluid for driving the piston B forward is admitted to the annular port S from the forward end of the bore L by means of cut away portions of the tail portion W of the piston B in the form of longitudinal grooves Y somewhat longer than 65 the distance between the forward end of the bore L to the annular groove S.

The motive fluid distribution for actuating the hammer piston B is as follows. Assuming the piston B to start from the position shown in Figure 1, the piston B is forced backwardly by pressure of motive fluid against the head V until the longitudinal grooves Y enter the larger bore L. The pressure in the rear end of the bore L 70 is previously reduced to atmosphere by free access through the port P to the exhaust port T in the chamber U. This exhaust is closed as the grooves Y are closed by the bore O. As the grooves Y enter the bore 75 L motive fluid is admitted to the port P and thence through annular groove Q to the bore L. This differential pressure on opposite faces of the piston head V drives the piston B forward to strike the steel C. 80 This cycle of operations is repeated indefinitely.

If the piston B is badly worn, motive fluid may leak past the piston head V into the upper bore so that the piston B will not 90 start to reciprocate automatically. This may happen if the piston B is very far forward so that grooves Y are closed to the annular groove S. In this position the pressure on the rear face of the piston head V 95 counteracts the pressure on the opposite face and the tool will not start operating.

Means is provided to counteract the effect of leakage which includes a passage Z through the piston B connecting the space 100 within the large bore L behind the head V at all times with the cut away portions or longitudinal grooves Y. This permits any leakage air in the bore L from building up substantial pressure and permits it to 105 pass to atmosphere through the exhaust port T.

The inlet port X preferably communicates with a bore b in a boss c on the cylinder wall A for connection with a throttle valve d.

The tamping bar C is held and guided in a pair of sleeves e and f fitting snugly in a bore g of an extension h of the cylinder A. The front head D acts as a retainer, there being a rubber buffer j interposed between the forward flange k of the front head D and the flanged sleeve f. The front head D is preferably bolted to a flange o of the cylinder A. As is usual in tools of this type the shank of the bar C is provided with a collar p to retain the bar in the tool and is afforded some movement by the spacing of the sleeves e and f.

I claim:

15. 1. A pneumatic hammer tool comprising a cylinder, a differential type piston within said cylinder, an exhaust port at one end of said cylinder, said piston being provided with cut away portions to provide communication between the ends of the cylinder and a port through the piston leading from one end of said piston to the cut away portion to provide constant communication from one end of the cylinder to the cut away portion 23 of the piston.
20. 2. A pneumatic hammer tool comprising a cylinder having a large bore and a small bore, a port leading from the large bore to the smaller bore, a piston adapted to reciprocate in said cylinder and having a head adapted to reciprocate in the large bore and a tail portion sliding in the smaller cylinder bore, an exhaust chamber in said cylinder adjacent the smaller cylinder bore, cut away portions in the tail portion of said piston adapted to co-operate with said port for connecting said port with said exhaust chamber and the large bore alternately, and a passage through said piston, the large bore being constantly in communication with said cut away portions.
30. 40. 3. A pneumatic hammer tool comprising a cylinder, a differential type piston within

said cylinder, an exhaust port at one end of said cylinder, said piston being provided with cut away portions to provide communication between the ends of the cylinder, and a port providing constant communication between one end of the cylinder and the space in the cylinder bore adjacent the cut away portions of the piston.

4. A pneumatic hammer tool comprising a cylinder, a differential type piston within the cylinder, an exhaust passage leading from the rear end of said cylinder to the cylinder bore intermediate the cylinder ends, an exhaust port at one end of said cylinder, communication between said exhaust passage and exhaust port being controlled by the smaller end of said differential type piston, longitudinal grooves in said piston to provide communication between said exhaust passage and said exhaust port and a port providing constant communication between one end of the cylinder and the space in the cylinder bore adjacent the cut away portions of the piston.

5. A pneumatic hammer tool comprising a cylinder, a differential type piston within the cylinder, an exhaust passage leading from the rear end of said cylinder to the cylinder bore intermediate the cylinder ends, an exhaust port at one end of said cylinder, communication between said exhaust passage and exhaust port being controlled by the smaller end of differential type piston, longitudinal grooves in said piston to provide communication between said exhaust passage and said exhaust port and a port providing constant communication between one end of the cylinder and the space in the cylinder bore adjacent the cut away portions of the piston.

In testimony whereof I have signed this specification.

WILLIAM FRANK ZIMMERMANN.
